UNITED STATES PATENT OFFICE.

CHARLES A. LEWIS AND HAROLD E. SMOCK, OF DAYTON, OHIO.

AUTOMATIC SELF-PROPELLED TOY TANK.

1,343,834.

Specification of Letters Patent. Patented June 15, 1920.

Application filed March 15, 1919. Serial No. 282,832.

To all whom it may concern:

Be it known that we, CHARLES A. LEWIS and HAROLD E. SMOCK, citizens of the United States, and residents of Dayton, in the county of Montgomery and State of Ohio, have invented a new and Improved Automatic Self-Propelled Toy Tank, of which the following is a full, clear, and exact description.

10 This invention relates to an improvement in self-propelled toy tanks, and has for one of its objects to provide a means which will automatically operate to cause the tank, when driven, to travel or move forward in an irregular course or path.

Another object is to provide a means for causing one end of the tank to move up and down in a vertical plane when driven.

20 A further object is to provide a self-propelled toy tank having guns movably mounted thereon and providing a means co-operating with said guns to cause them to be oscillated or moved when the tank is in motion.

25 A further object is to provide a self-propelled toy tank which is simple, yet rugged, in construction and is inexpensive to manufacture, which will simulate a real tank. This is accomplished in the present invention by providing a means which, when the tank is in motion, will automatically move the guns, cause the tank to move forward in an irregular path, and to cause one end of the tank to move up and down.

30 35 Other advantages of the invention will be apparent from the accompanying drawings and following description of one of the preferred forms of this invention, in which similar characters of reference refer to corresponding parts in the several views.

Figure 1 is a plan view of the invention with the top partly broken away to show the motor and drive connection, a means for oscillating the guns, and one of the means for obtaining the irregular forward motion;

Fig. 2 is a side elevation of Fig. 1;

Fig. 3 is a diagram serving to illustrate the irregular path taken by the tank.

40 In the preferred form shown in the drawings, the main tank body portion 1 may be suitably made of stamped sheet metal but any other suitable material may be used. Guns 2 are movably mounted in the body and

are shown projecting through barbettes 3. In the form shown the guns are carried at 55 pivot points 4 in a slot 5. The body portion which is carried by a rear axle 6 and a front axle 7 on which are mounted a pair of wheels 8 and 8' and 9 and 9', respectively. As a means to obtain an irregular 60 vertical or an up-and-down motion of one end of the tank, the wheels 9 and 9' are eccentrically mounted on the axle 7 so that as the wheels are turned one end of the tank body will be moved up and down in a 65 vertical plane, but any other suitable means may be used to produce this effect.

70 A suitable motor for self propulsion such as a spring motor 10 is provided to drive the axle 6 through the smaller gear 13 mounted thereon, meshing with the larger gear 12, which is mounted on the drum 11 and is actuated by the spring 10 when wound by the handle 14, through the pawl and ratchet connection 15 and 16, the function of which, it is apparent, is to permit the spring to be held in a wound condition. An axle 17 having the crank connections 18 and 19 is provided to turn with the gear 13. A link member 20 connects the crank 80 member 18 with the axle 7 to permit oscillating movement of one end of the axle 7 in the slotted opening 21 in the tank body. This is but one of the suitable means which is utilized to automatically obtain a movement in an irregular path when the tank is driven. Another link member 22 is shown connecting the crank 19 with a connecting plate 23 carried by one of the movable guns and from this other link members 24, 25 85 connect the connecting plate 23 with other guns 2-2, so that as the crank 19 reciprocates the link 22 such motion is communicated to the other pivoted guns through the respective connecting plate and link members to produce an oscillating motion of said guns. This too is only illustrative of one 90 of the many methods which may be used to produce the oscillating guns upon movement of the tank. On the top of the tank 100 body there is a turret 26 in which a gun 27 is mounted, which gun may also be suitably connected to the other guns to produce an oscillating motion thereof.

95 While only one preferred form of the invention has herein been shown, certain 105

changes and modifications thereof may be made without departing from the spirit and scope of this invention.

Having thus described our invention we claim as new and desire to secure by Letters Patent:

1. In a self-propelled toy tank mounted on wheels, a body therefor, a gun mounted thereon, means for moving said gun, and means for moving one of the wheels to cause the tank to move in an irregular path.
2. In a self-propelled toy tank having a body mounted on rear wheels and a front wheel mounted on an axle, one end of which is fixed and the other movable, a motor to drive said rear wheels, and means to reciprocate the other end of said axle to steer the tank in an irregular path when said rear wheels are driven.
3. In a self-propelled toy tank, a body, a motor therefor, a pair of wheels carrying one end of said body, driving mechanism connecting said motor and said wheels to move the tank, an axle, and another pair of wheels eccentrically mounted thereon to carry the other end of said body, whereby one end of said tank has an up-and-down motion when driven.
4. In a self-propelled toy tank a body mounted on a rear axle having a pair of wheels thereon, a front axle, a pair of wheels eccentrically mounted thereon, one end of said front axle being slidably mounted to permit an oscillating movement thereof, whereby when the tank is moved it has

an irregular forward movement, one end having an oscillating up-and-down movement.

5. In a self-propelled toy tank mounted on wheels, means for oscillating one end of said tank in a vertical plane when in motion, said means including eccentrically mounted wheels, and a means for oscillating one of said wheels in a horizontal plane to cause the tank when in motion to travel an irregular path.

6. A self-propelled toy tank comprising a body, wheels for one end of said body, a motor, a driving connection between said motor and said wheels, a wheel for the other end of said body carried eccentrically with respect thereto to produce an up and downward movement of the body when in motion, and a means for oscillating one of the wheels in a substantially horizontal plane to cause the tank to move in a substantially sinuous path.

7. A self-propelled toy tank including a body, guns therefor, wheels at each end of said body to carry same, a motor, a driving connection between said motor and a wheel at one end of said body, an eccentric connection for the wheel at the other end of said body to produce vertical oscillation thereof when said tank is in motion, and a connecting means between said motor and said guns for oscillating said guns.

CHARLES A. LEWIS.
HAROLD E. SMOCK.
